Attest:

UNITED STATES PATENT OFFICE.

EDWARD W. JOHNSON, OF CHICAGO, ILLINOIS, ASSIGNOR TO CHICAGO CARTON COMPANY, OF CHICAGO, ILLINOIS, A CORPORATION.

FOLDING PAPER CARTON.

Application filed September 20, 1920. Serial No. 411,453.

To all whom it may concern:

Be it known that I, EDWARD W. JOHNSON, a citizen of the United States, and a resident of Chicago, in the county of Cook and State of Illinois, have invented certain new and useful Improvements in Folding Paper Cartons, of which I do declare the following to be a full, clear, and exact description, reference being had to the accompanying drawings, forming a part of this specification.

The present invention has relation more particularly to that type of folding paper cartons designed to serve not only as a means for inclosing articles for shipment therein, but also as a means for attractively displaying said articles to prospective purchasers.

The invention consists in the features of novelty hereinafter described, illustrated in the accompanying drawings and particularly pointed out in the claims at the end of this specification.

Figure 1 is a plan view of a blank from which the carton will be made. Figure 2 is a fractional perspective view of the partially folded carton looking from the interior towards the end of the same. Figure 3 is a perspective view of one end of the carton with parts partially folded, the cover panels being omitted. Figure 4 is a perspective view similar to Fig. 3 but with the display panel and its end flaps in folded position. Figure 5 is a perspective view of an end portion of the carton with the cover panels in folded position.

My improved carton is preferably made of cardboard or like material ordinarily used for cartons of this general character. In the preferred embodiment of the invention, a sheet or blank from which the carton will be made is shown as cut and scored, as illustrated most clearly in Fig. 1 of the drawings.

A and A' designate, respectively, panels that will form the main longitudinal side walls of the carton; B designates the panel that will constitute the bottom of the carton and C designates the panel that will constitute the top of the carton, when these parts are in folded position. The panels A and A' are provided at their ends with the flaps α and α' , respectively, these flaps hav-

ing truncated portions as shown; the panel B is provided at its ends with the flaps b formed with locking extensions or tongues b' , notches b^2 being preferably formed at the junction of the extensions b' with the flaps b . The panel C is provided at its ends with the flaps c , these flaps being shown as formed with intersecting slits c' and c^2 whereby the tongues c^3 are formed on the flaps c . The panel C is formed with a series of openings c^4 that are suitably shaped to receive articles to be carried and displayed by the carton, such as tubes of tooth paste, mucilage, tire cement or the like, that will project through the top panel C and for a distance above the same. The parallel lines between the panels described and hereinafter described and between the panels and their end flaps represent scored lines that enable the parts of the sheet to be readily and accurately folded.

Next to the panel B is formed the back panel D to the ends of which are connected the end flaps d . As shown, the end flaps d are cut away opposite the end flaps b of the panel B and are formed with the locking extensions or tongues d' and notches d^2 , and the end flaps d are slitted, as at d^3 , to form the locking tongues d^4 . The corners of the end flaps d opposite the locking extensions d' are preferably rounded as shown at d^5 .

The panel D is connected with panels E and F, a line of slits or perforations e being preferably formed between the panels D and E to permit the panels E and F to be readily severed, if desired, after the carton has reached the retailer and the articles inclosed therein are to be displayed for sale. The panel E is formed with the end flange e' and the panel F is formed with the end flaps f having tongues f' at their ends.

The folding of the blank shown in Fig. 1 of the drawings to form the finished carton may be effected as follows: The end flaps α being turned upward at right angles to the panel A, this panel A will be turned to approximately vertical position (see Fig. 2), after which the end flaps c of the panel C will be turned vertically and the tongues c^3 of the end flaps c being forced slightly inward, the end flaps α will be passed between the tongues c^3 and the end flaps c . The end flaps α' of the panel A' will then be turned

upward and the panel A' may be swung to vertical position until its end flaps a' pass between the inner face of the upturned end flaps c and the end flaps a . The bottom 5 panel B will then be turned downward onto the upturned end flaps a , a' and c , and the end flaps b of the panel B will be folded inward and the tongues or extensions b' of the end flaps b will be passed into the longitudinal slits c' in the end flaps c of the panel C (see Fig. 3).

When the parts have been thus far folded, the panel C will be upon the bottom; but the carton will then be turned over bringing 15 the panel C uppermost, as shown in Fig. 3. The panel D will then be turned to vertical position and its end flaps d turned inwardly, the tongues or extensions d' of the end flaps d being passed between the end flaps b and 20 c (see Fig. 4). The panel D is of much greater width than the side panels A and A', so that when the parts are in the folded position last described, a considerable part of the upper portion of the panel D will be 25 exposed and will form a surface whereon advertising matter may be printed.

The panel E will then be turned downward, its end flaps being passed inside the end flaps d of the panel D and between the 30 end flaps d and the previously folded end flaps b and c , after which the panel F will be turned to vertical position (see Fig. 5) and its end flaps f will be turned inward and their tongues f' will be passed into the slits 35 d^s of the end flaps d of the panel D. When the parts are thus folded, the tubes of paste, mucilage or the like will be securely inclosed and the package will be ready for shipment.

When the articles contained within the 40 package are to be displayed, the tongues f' will be withdrawn from the slits d^s , the panels E and F will be unfolded and will be severed from the panel D along the perforated line e between the panels D and E, thus 45 leaving the carton in the condition shown in Fig. 4 of the drawings.

Having thus described my invention, what

I claim as new and desire to secure by Letters Patent is:—

1. A carton of the character described, 50 comprising a plurality of integral longitudinal panels and end flaps adapted to form the body of the carton, said sheet being provided with a display panel adapted to extend to a distance above the body of the carton, and 55 having end flaps interlocking with the end flaps of the carton body, the top of said display panel having connected thereto two additional panels one of which extends over the body of the carton and the other of 60 which extends downwardly adjacent the front wall of the carton body and has end flaps interlocking with the aforesaid end flaps of the display panel, and a line of perforations extending between the top of said 65 display panel and said additional panels to permit the latter to be readily torn away.

2. In a carton of the class described, the combination of a blank section comprising panels forming the top, bottom, front and 70 rear walls of a rectangular shell, and having end flaps interlocked with one another, another blank section comprising three panels, one of which folds up against the rear wall 75 of the rectangular shell and has a flap at each end extending forwardly along and interlocked with the corresponding end of the rectangular shell, another panel of said section extending over the top of the shell, and the third panel of said section being extended downwardly along the front wall of the shell and having a flap at each end interlocked with the corresponding end flap of the first mentioned panel of the latter section.

3. In a carton of the character described, 85 the combination of a container section, a cover hinged to the container section and having top, front and rear panels, a flap at each end of the rear panel interlocking with the end walls of the container section, and a 90 flap on each end of the front panel interlocked with the corresponding end flap of the rear panel.

EDWARD W. JOHNSON.
